[57] **CLAIM**

The ornamental design for a rectangular panel for construction toy set, as shown and described.

DESCRIPTION

FIG. 1 is a top plan view of a rectangular panel, showing our new design, the bottom being substantially identical; FIG. 2 is a side elevational view of the panel, all four sides being substantially identical; and, FIG. 3 is a perspective view of the panel from the top. The circular apertures shown in dotted lines form no part of the design.
